United States Patent Office

Des. 224,838
Patented Sept. 26, 1972

224,838

UTENSIL HANGER OR SIMILAR ARTICLE

David Douglas, 1119 Lincoln Blvd.,
Manitowoc, Wis. 54220

Filed Oct. 23, 1970, Ser. No. 25,628

Term of patent 14 years

Int. Cl. D7—99

U.S. Cl. D44—29

FIG. 1 is a front elevational view of a utensil holder or similar article showing my design;

FIG. 2 is a side elevational view; and
FIG. 3 is a top plan view.

I claim:

The ornamental design for a utensil hanger or similar article, as shown.
